J. LEVY

ATTACHMENT FOR TELEPHONES

Filed June 13, 1923

Jennie Levy, INVENTOR:
By
Medischeng, Van Dau, ATTORNEYS.

UNITED STATES PATENT OFFICE.

JENNIE LEVY, OF PHILADELPHIA, PENNSYLVANIA.

ATTACHMENT FOR TELEPHONES.

Application filed June 13, 1923. Serial No. 645,020.

To all whom it may concern:

Be it known that I, JENNIE LEVY, a citizen of the United States, residing at Philadelphia, county of Philadelphia, State of Pennsylvania, have invented a new and useful Attachment for Telephones, of which the following is a specification.

In a prior patent granted to me, I have disclosed a novel construction of a support for a telephone receiver which is adapted to sustain the latter in a horizontal or inclined position in proximity to the transmitter and my present invention comprises an attachment to the transmitter which is adapted to actuate the transmitter lever and hold it in the proper position during the conversation, the lever being manually operated and frictionally locked in the desired positions, as will be hereafter explained.

It further consists of novel features of construction and advantage as will be hereinafter pointed out.

For the purpose of illustrating my invention, I have shown in the accompanying drawing a form thereof which is at present preferred by me, since this will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of an attachment for telephones, embodying my invention.

Figure 2 represents a side elevation of the transmitter showing the lever in section.

Figure 3 represents a plan view of my invention in detached position.

Figure 4 represents a section on line 4—4 of Figure 2.

Figure 5 represents, on an enlarged scale, an end view of the manually operated lever and its adjuncts.

Similar numerals of reference indicate corresponding parts.

Referring to the drawings.

1 designates the post or standard of a telephone transmitter to the upper portion of which I secure the clip 2 by any suitable means having the arm 3 to the upper por-

tion of which I pivot, at 4, the lever 5 which has at one end the finger piece 6 and at the other end the fork 7 which engages the transmitter lever 8 of the usual construction. The arm 3 has the lateral extension 9 to which is secured the lower end 60 of the spring member 10 which has the bulge 11 therein which frictionally contacts with the lever 5. It will be understood that in the operation of my device, the receiver 12 normally rests upon the stand 13 and when it is desired to talk into the transmitter, the operator presses down on the finger piece 6, so that the parts assume the position seen dotted in Figure 2, the lever 8 of the usual construction being raised 70 by the internal spring mechanism of the usual character. When the conversation is ended, the lever 5 is caused to assume the position seen in full lines again, said lever being held in its proper position at all times 75 by its contact with the bulged portion 11 of the spring 10.

My device is adapted for the use of persons whose hands or arms have been amputated and it will be seen that the receiver 80 at all times normally remains as seen in Figure 1 but the operator by the use of the stump of his missing hand can manipulate the lever 5 and so control the movements of the standard transmitter lever 8.

My invention can be readily applied to standard transmitters by means of the clip 2, as is evident, and will be found to be cheap to manufacture and efficient in its operation.

It will now be apparent that I have devised a new and useful attachment for telephones which embodies the features of advantage enumerated as desirable in the statement of the invention and the above 95 description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what 105 I claim as new and desire to secure by Letters Patent, is:

In a device of the character stated, a

clamp adapted to be secured to a telephone transmitter, an arm carried by said clamp, an operating lever pivotally secured to said arm and having a forked end engaging the circuit opening and closing lever of the transmitting instrument, and a spring carried by said arm in operative alignment

with said operating lever to retain the same in either the operative or inoperative positions.

JENNIE LEVY.
